UNITED STATES PATENT OFFICE

JACOB M. SCHAFER, OF WASHINGTON, DISTRICT OF COLUMBIA, ASSIGNOR TO ARTHUR M. HYDE, AS SECRETARY OF AGRICULTURE OF THE UNITED STATES OF AMERICA

PROCESS FOR PREPARING ANTIGENS

No Drawing. Application filed November 25, 1930. Serial No. 498,106.

(GRANTED UNDER THE ACT OF MARCH 3, 1883, AS AMENDED APRIL 30, 1928; 370 O. G. 757)

This application is made under the act of March 3, 1883, as amended by the act of April, 30, 1928, and the invention herein described may be manufactured and used by or for the Government for governmental purposes without the payment to me of any royalty thereon.

My invention relates to the process of preparing antigens for use in the diagnosis of animal diseases and the products thereby produced.

Up to the present time there may be said to be two methods of testing fowls for pullorum diseases.

The first of these is known as the tube method, which is carried out by adding to suspensions of *Salmonella pullorum* different dilutions of the blood of chickens. In the case of a positive reaction the bacteria in the mixtures of antigen and serum clump and in time settle, leaving a clear fluid above. In the case of a negative reaction the tube remains uniformly clouded. This method requires the collection of considerable amounts of blood, the separation of the serum from the blood, the subsequent accurate dilution of the serum and the incubation of the test tubes in laboratories.

To overcome certain objections to the tube method there has been devised a rapid method. The antigen as generally employed consists of a heavy suspension of *Salmonella pullorum* in salt solution. A few drops of this heavy suspension are placed on a glass plate and a drop or two of properly diluted chicken serum or of blood are added directly to the bacterial suspension. In the case of a positive reaction if a bright light is placed beneath the glass plate on which the test is made it will be seen that the bacteria in the mixture above described have collected in clumps. In the case of a negative reaction there is only a uniform cloudy film without clumping. This rapid method works very well but on cloudy days it is difficult to read it and of course artificial illumination by electric light is frequently not available on farms. Furthermore, the antigens heretofore employed for the rapid method have not been well preserved so as to prevent contamination

and so as to insure that the pullorum bacteria which are used are killed.

In my work I have developed an antigen which consists of a heavy suspension of *Salmonella pullorum* in salt solution to which is added formaldehyde solution in sufficient amount to kill the bacteria. To this heavy suspension of *Salmonella pullorum* I have added crystal violet, an intensely staining dye, in an amount sufficient to stain the suspended bacteria a distinct blue or purple. If now a rapid test be carried out as described under the rapid method above, it is found that in the case of a positive reaction the bacteria collect in the form of blue or purplish clumps which are distinct, especially if the test is carried out on a glass plate with a white background.

The antigen prepared as I have prescribed does not seem to interfere with the agglutination reaction in any way nor does it cause agglutination when mixed with the blood of normal fowls. In the latter case, instead of the stained bacteria being arranged in definite clumps with clear spaces between them there appears a uniform faintly bluish film. Tests have shown that the pullorum organisms employed in the stained antigen are killed and therefore there is no danger of the spread of disease through the antigen. It has also been found that the dye employed aids in the prevention of contamination by extraneous organisms.

I have prepared a heavy suspension of *Salmonella pullorum* in 0.85 per cent salt solution killed by the addition of one per cent formalin and heavily stained by the addition of 0.03 per cent crystal violet.

The use of stained antigens as described above is new and useful in the diagnosis of animal diseases. Such stained antigens are superior to the colorless products in the following respects:

(1) They yield reactions of greater visibility and therefore they may be used in less concentrated and less costly form.

(2) Because of the antiseptic action of the dye itself the stained antigens are more readily and more perfectly preserved by the com-

mon antiseptics, such as phenol or formaldehyde.

(3) The reactions may be obtained on glass plates and dried for permanent record if desired.

(4) Because the bacteria are colored in the stained antigen, no special illumination is required to read the results of a test.

(5) The stained antigen shows little or no deterioration on standing, nor is it necessary to keep it under refrigeration.

Other antigens may be similarly stained, for example, the antigen used in the rapid agglutination test for abortion disease in cattle.

By my description above I do not wish to restrict my invention to the use of crystal violet and formaldehyde only since stains and preservatives other than crystal violet and formaldehyde may also be used and found suitable.

Having fully described my discovery I claim as my invention:

1. A diagnostic product comprising a heavy suspension of bacteria belonging to a disease producing class, an organic dye, such as is employed in staining bacteria, contrasting in color with the material to be tested, in amount sufficient to heavily stain the bacteria, an organic preservative which does not interfere with the diagnostic test, said product possessing the property when mixed with blood or serum, of rapidly agglutinating in the case of positive reactions into deeply stained clumps of bacteria which stand out in sharp contrast to the material to be tested, especially when viewed against a white background.

2. A diagnostic product comprising a heavy suspension of bacteria belonging to a disease producing class, an organic dye, such as is employed in staining bacteria, contrasting in color with the material to be tested, in amount sufficient to heavily stain the bacteria, said product possessing the property when mixed with blood or serum, of rapidly agglutinating in the case of positive reactions into deeply stained clumps of bacteria which stand out in sharp contrast to the material to be tested, especially when viewed against a white background.

3. A diagnostic product for detecting pullorum disease in fowls comprising a heavy suspension of *Salmonella pullorum* in a saline solution, crystal violet in amount sufficient to heavily stain the *Salmonella pullorum*, formaldehyde in sufficient amount to kill the *Salmonella pullorum*, said product possessing the property when mixed with blood or serum of fowls infected with pullorum disease of rapidly agglutinating into deeply stained clumps of bacteria which stand out in sharp contrast to the red blood cells, especially when viewed against a white background.

4. A diagnostic product for detecting pul-

lorum disease in fowls comprising a heavy suspension of *Salmonella pullorum* in a saline solution, crystal violet in amount sufficient to heavily stain the *Salmonella pullorum*, said product possessing the property when mixed with blood or serum of fowls infected with pullorum disease of rapidly agglutinating into deeply stained clumps of bacteria which stand out in sharp contrast to the red blood cells, especially when viewed against a white background.
